VACUUM CLEANER

Ivar Jepson, Oak Park, Gilbert R. Wolter, Elmhurst, and Alfred F. Ernstberger, Broadview, Ill., assignors to Sunbeam Corporation, Chicago, Ill., a corporation of Illinois

Filed Jan. 24, 1962, Ser. No. 163,490
10 Claims. (Cl. 15—337)

The present invention relates to vacuum cleaners, and more particularly to vacuum cleaners of the type commonly designated as upright vacuum cleaners.

Vacuum or suction cleaners, particularly useful for use in the home, have comprised two general types. One of these types, commonly referred to as an upright vacuum cleaner, has usually comprised a housing having at the underside of the forward end thereof a suction nozzle. To produce the necessary suction, an electric motor, a fan driven thereby, and usually a rotatable brush and beater arrangement driven by the motor are mounted in this same housing. Such an upright cleaner further includes a bag for receiving dirt removed during the vacuum cleaning operation. The second type of cleaner, commonly referred to as a tank or cannister-type cleaner, gets its name from its construction. It commonly comprises a tank or similarly shaped unit containing a motor driven fan for producing a suction, and connected to this tank through a flexible hose are various cleaning attachments. The present invention is directed to the first described or upright-type vacuum cleaner.

For many years, by far the most popular cleaner was the so-called upright-type cleaner. Initially the upright cleaner was primarily used for cleaning rugs and carpets, and it was felt that the motor-driven brush and beater was an essential part of the device to accomplish a good cleaning operation. The tank-type cleaner, at that time, relied primarily upon suction and had no means for beating or brushing the rug to aid in the cleaning operation. In recent years, the tank-type cleaner has become more popular due to the fact that attachments were provided, including turbine-driven brushes, for performing a rug cleaning operation commensurate with that performed by the upright cleaner. Additionally, upright cleaners, by virtue of the motor mounted in the same housing defining the suction nozzle were fairly large and could not readily be moved under low objects to perform a satisfactory cleaning operation. Also, the attachments commonly provided for upright cleaners to perform cleaning operations other than rug cleaning operations, were complicated to attach and the means for eliminating the suction at the nozzle in the housing and for rendering the rotating brush ineffective also were very complicated, often requiring putting a closure plate over the nozzle and removing the belt driving the brush and beater.

It would be desirable to provide an upright-type vacuum cleaner in which the housing defining the nozzle and supporting the rotatable brush and beater has a very low silhouette of the order of three inches or less so that it may be moved under almost any piece of furniture with the same facility as the nozzle of the tank-type cleaner. Additionally, it would be desirable to provide an upright-type cleaner whereby attachments could readily be connected thereto for performing certain cleaning operations other than the cleaning of rugs or carpets wherein the mere insertion into the suction area of the vacuum cleaner of the tube connected to the attachment not only disables the drive to the brush and beater, but also closes off the suction to the primary suction nozzle.

2

Accordingly, it is an object of the present invention to provide a new and improved upright cleaner having the desirable features enumerated above.

It is another object of the present invention to provide a new and improved upright-type vacuum cleaner whereby the motor for supplying the suction and driving the brush and beater arrangement is mounted adjacent the handle portion of the upright cleaner.

Still another object of the present invention resides in an improved upright vacuum cleaner wherein a first housing defining the suction nozzle is pivoted to the lower end of a second housing containing a motor driven fan drivingly connected to a rotatable brush in the first housing.

15 A still further object of the present invention resides in an upright-type vacuum cleaner with improved means of disabling the brush and beater arrangement upon the mere insertion of a portion of the attachment into the suction area of the vacuum cleaner.

20 Still another object of the present invention resides in improved counterbalancing means for counterbalancing the upper of the pivotally related housings so that the weight of the motor and fan in the housing secured to the handle need not be supported by the person manipulating

25 the cleaner.

It is another object of the present invention to provide an upright-type cleaner in which the housing defining the nozzle and housing the rotatable brush is sufficiently low so that it can be moved underneath almost

30 any type of furniture in the same manner that the nozzle of the tank-type cleaner can be manipulated.

Further objects and advantages of the present invention will become apparent as the following description proceeds and the features of novelty which characterize the invention will be pointed out with particularity in the claims annexed to and forming a part of this specification.

For a better understanding of the present invention, reference may be had to the accompanying drawings in

40 which:

FIG. 1 is a front perspective view of the upright-type vacuum cleaner of the present invention;

FIG. 2 is a side elevational view of the cleaner of FIG. 1 with certain portions thereof shown in section 45 taken substantially on line 2—2 of FIG. 1;

FIG. 3 is a greatly enlarged bottom view of the lower housing portion of the upright-type vacuum cleaner of the present invention and the lower portion of the upper housing pivotally connected to the lower housing, with certain portions cut away more clearly to illustrate the present invention and with the upper housing pivoted to its lowermost position;

FIG. 4 is a sectional view taken on line 4—4 of FIG. 3, assuming that FIG. 3 shows the complete structure and with certain other portions broken away;

FIG. 5 is a sectional view taken on line 5—5 of FIG. 3, again assuming that FIG. 3 shows the complete structure;

FIG. 6 is a greatly enlarged fragmentary sectional view taken on line 6—6 of FIG. 3, also assuming that FIG. 3 shows the complete structure;

FIG. 7 is a sectional view taken on line 7—7 of FIG. 6, assuming that FIG. 6 shows the complete structure;

FIG. 8 is a fragmentary sectional view taken on line 8—8 of FIG. 6, again assuming that FIG. 6 shows the complete structure;

FIG. 9 is an enlarged fragmentary sectional view taken on line 9—9 of FIG. 3;

FIG. 10 is a fragmentary sectional view taken on line 10—10 of FIG. 9, assuming that FIG. 9 shows the complete structure;

FIG. 11 is an enlarged fragmentary view of a portion

of FIG. 5 but with the pulley and clutch portion thereof shown in section;

FIG. 12 is an inside view of a cover member of the device of the present invention taken in the direction of the arrows 12—12 in FIG. 4, assuming FIG. 4 shows the complete structure; and

FIG. 13 is an exploded perspective view of certain portions of FIG. 11 plus a portion of a cleaner attachment to illustrate how a cleaner attachment connected to the upright vacuum cleaner of the present invention disables the brush and beater arrangement and diverts the suction from the primary nozzle to the attachment.

Briefly, the present invention is concerned with an upright-type vacuum cleaner comprising a very low, flat, wheel-mounted unit or first housing defining the principal nozzle at the bottom front thereof and having a rotatable brush and beater arrangement contained therein adjacent said nozzle. The lower housing or wheel-mounted unit includes simple counterbalancing means for counterbalancing an upper housing and handle member pivoted to the wheel-mounted unit, the upper housing containing the motor and suction producing means in the form of a fan. Means are, of course, provided to transmit the suction from the upper housing, where it is produced, to the wheel-mounted unit, and, specifically, the primary nozzle defined therein. Additionally, the upper housing includes a disposable dust bag into which dirt and other foreign matter, which is sucked through the nozzle portion of the device, may be retained for subsequent disposal. Power is transmitted from the motor through a clutch to a jack shaft located in the wheel-mounted unit on the pivotal axis between this unit and the upper housing, and then power is also transmitted from this jack shaft to the brush and beater arrangement rotatably mounted in the lower housing adjacent the primary nozzle. The upper housing includes a first removable cover, affording access to the disposable bag, and a second removable cover adjacent the clutch, affording access to the suction area. This second removable cover includes an access opening through which one may insert the tube portion of an attachment, and the mere insertion of this tube portion cuts off the suction passageway leading to the lower housing and, at the same time, actuates the clutch to terminate the rotation of the jack shaft driving the brush and beater arrangement.

Referring now to the drawings, there is illustrated in FIGS. 1 and 2 an upright-type vacuum cleaner, generally designated by the reference numeral 20. The vacuum cleaner 20 comprises a lower or first housing comprising a wheel-mounted unit, generally designated as 21, which is a very low unit having an overall height of the order of three inches or less. Specifically, the wheel-mounted unit 21 includes support means in the form of a pair of front wheels 22 and a pair of rear wheels 23, best shown in FIG. 3 of the drawings. In addition to the wheel-mounted unit 21, the upright vacuum cleaner includes a second or upper housing, generally designated at 24, the lower end of which is pivotally connected in a manner described in detail hereinafter to the rear of the unit 21. The upper end of the upper housing 24 is connected to a handle member 25, preferably formed of a molded plastic.

The handle member 25 is of tubular configuration comprising an upper hand grip portion 25a disposed at an angle relative to the main body portion of the handle member 25 and a lower, flared, open bottom cup-shaped portion 25b, having such a size and configuration to smoothly conform to the upper end of the top of upper housing 24 when secured thereto, as is clearly shown in FIGS. 1 and 2 of the drawings. Disposed within and adjacent the lower open end of the flared portion 25b are a plurality of bosses 25c integrally molded with the handle member 25, containing either tapped openings or a tapped insert for receiving suitable fastening means 27 for securing the handle 25 to the upper end of the upper housing 24.

To accommodate a suitable power cord, generally designated at 28, the handle member 25 is provided with a suitable opening through which this cord can extend. Preferably a strain relief 29 is secured in this opening in any well-understood manner. Also, for the purpose of supporting a suitable control switch for the electric motor of the vacuum cleaner of the present invention, the front of the hand grip portion 25a of handle member 25 is provided with a suitable opening 30 for supporting a removable plate 31, which plate supports the conventional control switch 32, having the switch knob 32a. Preferably the handle member 25 includes bosses 25d and 25e for suitable securing means which together with brackets 34 and 35 removably secure the switch plate 31 and switch 32 in position.

For the purpose of removably securing or latching in position a cover for the upper housing 24, described hereinafter, and also to provide a cord support, there is pivotally mounted to the flared portion 25b of handle member 25 a combined latch and cord support 36, pivotally mounted as indicated at 37. The upper portion 36a of the element 36 is a cord hook for supporting the power cord 28 when the vacuum cleaner is not in use, and also a manual lever for actuating the latch portion 36b of element 36 which, in turn, cooperates with a latch plate 38 secured to a cover defining part of upper housing 24.

Considering now the upper housing 24, the upper end of which is connected to the handle member 25, it comprises a main elongated, rectangular, boxlike member or container 40, open on one side, preferably formed of a molded plastic or the like, and a pair of cover members 41 and 42 for closing the open side of container 40. The upper housing 24, defined by the container 40 and covers 41 and 42, is effectively divided into two chambers (FIG. 2), an upper chamber, generally designated at 43, defining a dust bag chamber, and a lower chamber 44, defining a motor and fan chamber. The cover 41 effectively is a cover for the dust bag chamber and is intended to be readily removable by the housewife to remove and replace dust bags as desired, while the cover 42 is effectively a cover to afford access to the motor and fan and to support the same, as will become apparent from the ensuing description.

To provide the desired strength and rigidity, the elongated sidewalls 40a of container 40 of the upper housing 24 are preferably of a double wall construction (best shown in FIG. 3) with a plurality of connecting ribs 40b between these walls, the space between the ribs providing a plurality of recesses for receiving cooperating integral projections 41a (FIG. 2) of the dust bag chamber cover 41, thus providing a sort of interlocking arrangement when the cover 41 is in position. The upper end of container 40 is defined by an end wall 40c (FIG. 2) through which fastening means 27 extend to secure the handle member 25 thereto. To further increase the rigidity of the upper end of housing 24, a stiffening plate 46 (FIG. 2) extends across one end of the open side of the container 40 and is secured to the side walls, by suitable screws or fastening means not shown in the drawings. Sufficient rigidity for the lower end of container 40 is provided by the cover 42, which is described in greater detail hereinafter, and which is secured thereto as by suitable fastening means 48 (FIG. 3) extending through openings 48a (FIG. 12) in cover 42.

Preferably the lower end wall 40d of container 40 is provided at the center thereof with an opening for accommodating a suitable lens 50 (FIGS. 1, 2, 4 and 5), which lens is adapted to permit light rays from a suitable light bulb 51 mounted within the motor chamber 44 to be directed to light the area adjacent the front of wheel-mounted unit 21. The edges of the opening in container 40 are designed to support lens 50 which may be secured thereto in any suitable manner. If desired, the bottom of container 40, which defines the front of upper housing

24, may be provided with a slightly recessed area for receiving a decorative plate 52 (FIGS. 1 and 2).

The dust bag chamber cover 41, preferably molded from a suitable plastic, has the latch plate 38 secured to the upper end and a cord clip 53 (FIGS. 2 and 4) secured to the lower end spaced from the cord clip portion 36a of element 36. The lower end of cover 41 is provided with a lip 41b (FIG. 4) which is inserted beneath the adjacent end of cover 42 and, hence holds this lower end in position while the latch portion 36b removably holds the upper end of cover 41 in position.

The lower or motor chamber cover 42 is also preferably molded from a suitable plastic and is adapted to have a motor and fan unit or suction producing means, generally designated as 54, secured thereto as by screws or fastening means 56 (FIG. 3) passing through suitable openings 56a (FIG. 12), so that when cover 42 is secured to container 40 by fastening means 48 extending through openings 48a, the motor and fan unit will be properly supported in chamber 44 in upper housing 24. To permit fan exhaust air to escape from the motor chamber 44, the cover 42 is provided on either side with a plurality of notches 57 defining exhaust openings (FIGS. 1, 2 and 12). The lower central section of cover 42 is raised as indicated at 42a and this section is provided on the inside thereof with a plurality of grooves, such as 58 and 59 (FIGS. 4, 5, 11 and 12), to receive portions of fan housing means described hereinafter defining a scroll-like fan inlet chamber 62 and a belt or drive chamber 63 (FIGS. 3, 4 and 5), the cover 42 effectively defining a cover for said chambers. A crescent shaped opening 64 (FIGS. 12 and 13), to permit the use of attachments as described hereinafter, is defined in cover 42 to afford access to the correspondingly shaped end of fan inlet or suction passageway 62. A removable cover 65 for this opening is provided. The lower end of raised portion 42a of cover 42 terminates in a lateral flange or lip 42b, best shown in FIGS. 4, 5, 6 and 12 of the drawings.

The wheel-mounted unit 21 includes a shallow boxlike housing 70 of generally rectangular construction, although slightly narrower at the rear than at the front. This housing 70 is preferably a unitary casting of light weight metal or the like open at the bottom with the side walls defined by a depending peripheral flange 70a extending around the entire periphery except for a short discontinuity at the center of the rear wall defining a notch or opening 72 (FIGS. 3 and 7) for receiving therein a projection from the upper housing to provide the pivotal relationship referred to above. Actually, the notch 72 partially extends into the top wall of housing 70, as is shown in FIG. 1 of the drawings. The housing 70 includes a plurality of depending integral wall portions or partitions 70b, 70c and 70d (FIG. 3), the bottoms of which are all level with the bottom of flange 70a thereby dividing the interior of housing 70 into a plurality of downwardly opening chambers 74, 75, 76, 77 and 78. The chambers 74 and 75 are wheel chambers defined by the partitions or wall portions 70b and 70c and the peripheral wall portion 70a, the partitions 70b and 70c being somewhat L-shaped.

To support housing 70, the wheels 22 and 23 are disposed in the wheel chambers 74 and 75 and are rotatably supported on suitable shafts mounted in these chambers. Specifically, one front wheel 22 and one rear wheel 23 are rotatably mounted on shafts 79 and 80, respectively, supported by means including the walls defining the wheel chamber 74. In a similar manner, the other wheel 22 and the other wheel 23 are rotatably mounted in wheel chamber 75 on suitable shafts 81 and 82, respectively, suitably supported by means including the walls defining this chamber or by suitable brackets integrally formed with the chamber walls.

The chambers 76 and 77 merge at the front of housing 70 into a brush and beater chamber 83 (FIGS. 4, 5 and 9) extending across the front of housing 70 which con-

tains a suitable brush and beater device, generally designated as 84, described in detail hereinafter and best shown in FIGS. 3, 4, 5, 9 and 10 of the drawings. This device 84 includes a pulley or other drive means designated as 85. The chamber 76 might be designated as a drive chamber closed at the rear for housing drive means such as the belt 86 drivingly connected to pulley 85. The chamber 77 might be designated as the suction passageway for dirt and the like sucked into the brush and beater chamber 83 which is directed toward the open notch 72 at the rear of housing 70. The chamber 78 might be designated as the swivel and counterbalance chamber, the rear of which is defined by the boundaries of notch 72. The wall portion 70d is of somewhat V-shape, as clearly shown in FIG. 3 of the drawings, and it defines chamber 78 and part of chambers 76 and 77. By virtue of the shape of wall portion 70d, the air or suction passageway 77 is quite wide as it approaches the brush chamber 83 where it merges with drive chamber 76 and is quite narrow as it approaches the notch 72 but to one side thereof.

In order pivotally to relate the wheeled unit 21 and the upper housing 24 while at the same time providing mounting means for a drive pulley for the belt 86 on the pivotal axis between unit 21 and housing 24 and further providing a relatively sealed air or suction connection between suction passageway 77 and suction producing means 54, the ends of the V-shaped wall section 70d adjacent the notch 72 are cut away to define bearing receiving notches for supporting a pair of spaced aligned end bearings 88 and 89. These end bearings each have a side elevational view, as shown for the end bearing 88 in FIG. 5 of the drawings, including lateral extensions 88a and 89a, respectively. The edges of the wall portion 70d defining the bearing receiving notches are grooved as is also the edge of notch 72 defined by wall 70d to receive a tongue on the cooperating portions of end bearings 88 and 89. These tongues are designated as 88b and 89b, respectively, and the grooves as 91. With this arrangement, end bearings 88 and 89 can be slipped into the bearing receiving notches and the tongue and groove arrangement will securely position them except for means described hereinafter to hold them in such notches. Each of end bearings 88 and 89 includes a portion projecting into swivel and counterbalance chamber 78 defining a pair of spaced aligned cylindrical bearing surfaces designated as 88c and 89c, respectively, best shown in FIG. 7 of the drawings. Preferably, the end bearings 88 and 89 are formed of a die cast material, such as zinc or the like, and the spaced aligned cylindrical bearing surfaces 88c and 89c of these end bearings are fairly accurately defined as by machining or the like.

The end bearing 88 has a large opening 93 there-through defining a suction passageway connecting passageway 77 with the space between end bearings 88 and 89. The end bearing 89, on the other hand, is essentially a closed end bearing since no air passageway is defined therethrough. However, it is a jack shaft supporting bearing and, in accordance with the present invention, is provided with a central opening 94 for supporting a bearing 95 for a jack shaft 96. One end of this jack shaft extends into the belt or drive chamber 76 while the other end is disposed in the space between the end bearings 88 and 89. Suitable pulleys 97 and 98 are secured to the ends of the jack shaft 96. The pulley 97 is adapted to drive the belt 86 which is also reeved on pulley 85. In the drawings, the belt 86 is illustrated as what is commonly referred to as a poly-V belt and, consequently, poly-V pulleys 85 and 97 are illustrated although obviously they might comprise pulleys for accommodating the well-known timing belt. Actually, the pulley 98 is illustrated as a pulley for accommodating a timing belt 100. Obviously it might be similar to pulley 97 and belt 100 might be similar to belt 86. Timing belt 100 is

reeved about a pulley 101 drivingly connected to the motor and fan unit 54 supported in upper housing 24 through clutch means described hereinafter.

From the above description it will be evident that since the axis of jack shaft 96 is coincident with the axis of the cylindrical surfaces 88c and 89c defining the pivotal axes between unit 21 and housing 24, relative pivotal movement of unit 21 and housing 24 about this axis will in no way effect the drive connection between pulleys 98 and 101 or between pulleys 85 and 97.

It will be appreciated that the upper housing 24 and associated handle 25 containing the suction-producing unit 54 therein is pivoted to the wheel-mounted unit 21. The weight of the upper housing portion and, particularly, the weight of the suction producing unit 54 without suitable additional means would require the housewife to carry a relatively heavy weight and would tend to cause the upper housing unit 24 and handle portion 25 to move from the position shown in FIGS. 1 and 2 to the position shown in FIGS. 4 and 5. For the purpose of reducing or effectively eliminating the weight of the upper housing unit, the suction producing unit 54 is, of course, placed very close to the pivotal axis, pivotally relating the housing 24 and the wheel-mounted unit 21. In addition to that, there is provided what might be termed an effective counterbalancing unit, generally designated at 104, and best shown in FIGS. 3, 6 and 8 of the drawings. This effective counterbalancing unit 104 comprises a cylinder or drum 105 formed of two cup-shaped members 105a and 105b having their closed ends disposed in face-to-face engagement, as best shown in FIG. 8 of the drawings, which cup-shaped portions are welded or otherwise secured to each other and to a shaft 106, the weldments being designated as 107 in FIG. 8 of the drawings. Thus, the drum 105 is rigidly mounted to the shaft 106, which shaft is journaled in the extensions 88a and 89a of end bearings 88 and 89, respectively, so as to be disposed in chamber 78. Housed within the cup-shaped member 105b of cylinder or drum 105 is a coiled torsion spring 108, the ends of which spring include lateral projections, such as 108a and 108b, indicated in FIG. 8 of the drawings. One of these projections 108a extends through suitable aligned openings in the adjacent end walls of cup-shaped members 105a and 105b, which are preferably welded to each other and to the shaft 106. For the purpose of torsionally relating the spring 108 to the rotatable drum 105 and some stationary object, there is provided a coil spring retainer 110, preferably in the form of a cylindrical die casting having an outer diameter slightly less than the diameter of the torsion spring 108 and a closed end portion 110a, having an opening therein for receiving the lateral projection 108b at the end of coil spring 108 remote from projection 108a. As illustrated, this projection 108b extends completely through the end 110a of coil retainer 110 so as to engage a projection 70e from the wall portion 70d. In this way the coil spring retainer 110 is held stationary and, consequently, so is the end 108b of spring 108. Thus, rotation of the drum 105 will torsionally stress the torsion spring 108. In a device built in accordance with the present invention, the torsion spring 108 was capable of producing a tangential force in excess of sixteen pounds with a three hundred sixty degree rotation of the drum 105 relative to coil spring retainer 110.

In order to relate the counterbalancing unit 104 positioned in chamber 78 in unit 21 to the upper housing 24, there is provided a ribbon spring 112 having on end thereof connected to the exterior of drum 105 so as effectively to be capable of being wound on drum 105 with rotation thereof. As specifically illustrated in the drawings, the drum 105 is provided with integral hook-like projections 105c (FIGS. 3, 6 and 8), which projections engage suitable openings 113 (FIG. 3) defined in one end of the ribbon tension spring 112. Preferably this spring passes over a cylindrical swivel portion 115a of a fan housing portion

115, described in detail hereinafter. The cylindrical swivel portion 115a, as best shown in FIGS. 6 and 7 of the drawings, is a cylindrical member the interior of which is divided into two sections by a partition 115b. The swivel 115a is received within the notch 72 and is provided at either end with counterbores 116, which counterbores pivotally engage the cylindrical bearing surfaces 88c and 89c, as clearly shown in FIG. 7 of the drawings, thereby pivotally supporting the swivel 115a about the axis of jack shaft 96.

Swivel 115a, as mentioned above, is divided by partition 115b into two chambers; a suction chamber 117 and a pulley chamber 118. The pulley chamber 118 receives the end of jack shaft 96, supporting pulley 98 and the belt 100, while the chamber 117 is connected to the suction passageway 77 through the opening 93 in end bearing 88. The cylindrical exterior of swivel 115a provides a bearing surface for the ribbon spring 112 which is secured to the fan housing portion 115, as indicated at 119, thus tending to bias the upper housing to the position shown in FIGS. 1 and 2 and effectively counterbalancing the weight of the suction producing means 54 and the upper housing 24.

As was mentioned above, the brush and beater device 84 driven from the jack shaft 96 through the belt 86 extends across the front of the housing 70 within brush and beater chamber 83 forwardly of the L-shaped wall sections 70b and 70c. As is best shown in FIGS. 3, 4, 5, 9 and 10, the brush and beater device 84 comprises a shaft 120 for supporting three separate brush and beater sections 121, 122 and 123, as well as the pulley 85, the pulley 85 being disposed between brush and beater sections 122 and 123. The three brush and beater sections, 121, 122 and 123 of the brush and beater unit 84 are all essentially the same except for some variations in length and the fact that these sections are angularly displaced relative to each adjacent section by approximately one hundred and twenty degrees. Each brush and beater section 121, 122 and 123 includes a tubular brush support section, generally designated as 126, and except for the length thereof these tubular sections are identical for each brush section 121, 122 and 123, and only one will be described in detail. The cross-section of the three brush supporting tubes 126 is clearly indicated in FIGS. 4 and 10 of the drawings, each tube including a deformation of the periphery thereof to define an elongated T-shaped slot 127 (FIG. 10) for slidably receiving from either end thereof a brush element 128 having a backing strip of suitable material supporting a plurality of tufts 129. The brush supporting tubes 126 also include a depressed portion 130 generally opposite the T-shaped slot 127, providing a space for a beater bar 131, described hereinafter. The brush tubes 126 are preferably formed of an extruded aluminum alloy.

For the purpose of supporting the three tubes 126 which may have slightly different lengths from the shaft 120, there are provided a pair of brush end members 133 which are substantially identical, one of which is shown in section in FIG. 9 of the drawings, a divider member 134 (shown only in FIG. 3 of the drawings), and the brush pulley 85 heretofore described. The end members 133, the pulley 85 and the divider member 134 are preferably all formed as light weight castings of a zinc-based alloy or the like and the end members 133 are each provided with a cooperating projection of the configuration of the tubes 126, while the pulley 85 and the divider member 134 are provided with two projections, one at either side, so that these projections may be received in the ends of the tubes 126, as clearly shown in FIG. 9 of the drawings insofar as the brush end member 133 and the pulley 85 is concerned. It should be understood that the pulley 85 and the divider 134 have the projections received in tubes 126 displaced in such a manner that the adjacent tubes are angularly displaced by one hundred twenty degrees, or more specifically that the adjacent brush sections 128

are displaced from each other by one hundred twenty degrees.

Preferably the brush ends 133 are provided with an end opening central recess 133, which is connected to a relatively large circular recess 139 at the outer end of each of the brush ends 133. A circular nut 140 threadedly mounted on the shaft 120 disposed within the recess 133 permits clamping the assembled brush sections heretofore described including the ends 133 to the shaft 120. A similar nut may be employed at the other end, or, if desired, a suitable washer and retaining ring may be substituted for the clamping nut 140 since it is only necessary to have a clamping nut at one end. The ends of the shaft 120 are preferably supported in suitable bearings 142, which in turn are supported in a combined dust cap and bearing support member 141, clearly shown in FIG. 9 of the drawings. The combined dust cap and bearing support includes a tubular projection 141a receivable in the recess 133 for supporting the bearing 142. Preferably a spherical thrust member 144 is disposed within the shaft receiving recess of element 141, as clearly shown in FIG. 9 of the drawings, to take up the end thrust of the shaft 120. The combined bearing retainer and dust cap 141 includes an enlarged disk-shaped portion 141b receivable within the larger recess 139, thus preventing threads and the like from entering the bearing. Furthermore, each combined bearing support and dust cap 141 includes a rectangular extension 141c receivable within a downwardly directed recess 147 defined in the wall portion 70a of housing 70 at each end of brush and beater chamber 83. Suitable clamping means not shown may be provided to retain portion 141c of the combined bearing support and dust cap 141 in the recesses 147, which recesses are also rectangularly shaped so that the elements 141 are rigidly held therein.

In accordance with the present invention, the beater bars 131 are preferably formed of an extruded plastic having the cross-sectional shape clearly shown in FIG. 10 of the drawings. The beaters may be provided at either end thereof with suitable pivotal supports designated as 149 in FIGS. 9 and 10 of the drawings. These pivotal supports may comprise pins extending entirely through the extruded beater bars, pins inserted at either end thereof, or preferably, as illustrated in FIG. 9 of the drawings, may comprise projections of the end members supporting the beaters bars, such as the end members 133, the pulley 85 and the divider 134. It will be appreciated that the beater bars 131 are pivotally mounted one in each of the sections 121, 122, and 123, and like the brush elements 128, are displaced in adjacent sections by an angle of one hundred twenty degrees. It will be apparent from FIG. 10 that each beater bar 131 has on the active side thereof an end protrusion 131a and a center protrusion 131b. When the beater and brush unit 84 is rotated, centrifugal force will cause pivotal motion of the beater elements 131. With the described arrangement, the beater bars 131 present the relatively large single area of protrusion 131a into contact with a soft nap rug and also allow the two separate areas of protrusions 131a and 131b to engage a heavy nap rug when beater bar 131 is only partially extended due to the thick nap. Furthermore, with the arrangement described, a very simple beater bar is provided which can be manufactured at a very low cost. In applying the beater bars 131 to the brush and beater unit 84, the plastic construction thereof will permit them to be deformed sufficiently to permit the pin portions, such as 149, to be received therein, as is clearly evident in FIG. 9 of the drawings.

For the purpose of defining a primary or suction nozzle in the unit 21, for holding the end bearing members 88 and 89 and the means supported thereby in the bearing receiving notches, and for completing the suction passageway 77, there is provided what might be termed a dust pan 150, best shown in FIGS. 3, 4, 5, 6, 7, 8 and 9 of the drawings. This dust pan has a some-

what T-shaped area and the stem of the T completely encloses the chambers 77 and 78 while the head of the T overlies the beater and brush chamber 83 defining the suction nozzle 151 in the form of elongated openings 151a and 151b. These openings 151a and 151b are separated by a narrow section 150a of dust pan 150, which in effect is a guard preventing one from coming into contact with the drive belt 86 and brush pulley 85 disposed in chamber 76. The wheel chambers 74 and 75 are not covered by dust pan 150. To provide the desired dust seal, a suitable gasket is interposed between dust pan 150 and the lower edges of the wall portions 70b, 70c, 70d and part of the wall portion 70a defining the beater and brush chamber 83. This gasket is not shown in the drawings, but is preferably formed of cork or other suitable material to provide the desired seal.

In order to secure the dust pan 150 to the housing 70, the front of the dust pan 150 is preferably provided with a hook shaped portion 150b for engagement, as clearly shown in FIGS. 4 and 5 of the drawings, with a lateral projection from the wall portion 70a at the front of housing 70 thereby securely locking the front of the dust pan to the housing 70. The remainder of the dust pan is preferably secured by suitable fastening means 154 and 155 to tapped openings defined in wall portions of housing 70. In order to accommodate the swivel 113a, the dust pan 150 is preferably provided with a depression 150c, best shown in FIG. 4 of the drawings.

For the purpose of preventing the unit 21 of the vacuum cleaner 20 from damaging furniture or walls when moved into engagement therewith, there preferably is provided a bumper guard 156, formed of a rubber or a molded plastic, such as a vinyl material or the like, which is suitably secured to the outside of the wall portion 70a. As is best shown in FIGS. 4, 5 and 9, this bumper guard has a relatively hollow construction so that it may readily deform when engaged by furniture, walls or the like.

Considering now the fan and motor unit 54 in more detail, the fan housing in addition to the portion 115 described above includes a housing portion 157 generally in the form of a relatively flat plate bolted or secured by fastening means 158 to the fan housing portion 115. As best shown in the drawings, the housing portion 115 includes on the upper side thereof, as viewed in FIGS. 4 and 5 of the drawings, means defining a generally circular fan chamber 159. This fan chamber terminates in a tangential exhaust passageway 160 in the form of a tubular member 161 defined by cooperating extensions 115c and 157a of fan housing portions 115 and 157, respectively. Moreover, tubular member 161 is provided near its open end with an exterior peripheral groove 163 for accommodating a garter spring dust bag clamping member 164 which might be an endless coiled spring, a rubberband or the like, the purpose of which will become apparent from the ensuing description. The fan housing portion 115 on the side opposite the fan chamber 159 is provided with elongated wall portions defining the scroll-like fan inlet chamber 62 and the belt or drive chamber 63 (FIGS. 3 and 7). As illustrated in FIG. 3, one side of the fan inlet chamber 62 and one side of the drive chamber 63 are defined by a U or hairpin-shaped wall portion 115d, the legs of the U or hairpin terminating in the cylindrical swivel 115a. An additional wall portion 115e, as clearly shown in FIG. 3 of the drawings defines the common wall between the suction and drive chambers 62 and 63, and includes a circular section surrounding the pulley 101 and defining with a similar circular section of wall portion 115d the scroll-like portion of passageway 62.

As is best shown in FIGS. 4 and 5 of the drawings, the fan chamber 159 is provided with an axial inlet opening 175 which connects the fan chamber 159 with the scroll-like suction passageway 62. The open side of the scroll-like suction passageway 62 is closed by the cover

42 and, as best shown in FIG. 11 of the drawings, the wall portion 115d extends into groove 58 and the wall portion 115e extends into groove 59 defined in the cover 42. Preferably a suitable scroll gasket, not shown in the drawings, is interposed between the edges of wall portions 115d and 115e and the cover 42 to provide a sealed suction chamber. Also a gasket 176 (FIGS. 4 and 6) is interposed at the junction of the swivel 115a and lateral flange or lip 42b of cover 42. It will be understood that the suction passageway 62 enters the interior of swivel 115a to one side of partition 115b as clearly indicated in FIG. 7 of the drawings, and a relatively large unimpeded passageway is provided from the brush chamber 83 to the tubular fan outlet passageway 160. Similarly, the drive passageway 63 enters the swivel 115a on the other side of partition 115b. Preferably the fan housing portions 115 and 157 are die castings of a light weight metal.

The fan and motor unit 54 includes an electric motor 178 having the conventional motor shaft 179 to which a fan 180 including the conventional fan blades 180a and the pulley 101 are secured. This fan 180 is disposed in fan chamber 159 and draws air through the axial inlet 175 and discharges it through the tangential exhaust passageway 160. The particular construction of the electric motor 178 forms no part of the present invention, but it preferably is a compact, relatively flat motor so as to minimize the space required therefor in upper housing 24. As illustrated in the drawings, the electric motor 178 is preferably secured by fastening means 184 to a plurality of projections 157b integrally formed with the fan housing portion 157. Suitable motor and fan bearings are provided and supported by fan housing portion 157. Electric energy is supplied to motor 178 and lamp 51 from power cord 28 and is controlled by the switch 32. It will be understood that when the switch 32 closes the circuit to electric motor 178 and lamp 51, that the fan 180 will be rotated at high speed to produce the desired suction and pulley 101 attached to motor shaft 179 through a clutch to be described hereinafter will drive the jack shaft 96, which in turn will rotate the brush and beater unit 84.

In accordance with the present invention, there is mounted within the dust bag chamber 43 of upper housing 24, a dust bag 186, best shown in FIGS. 2 and 4 of the drawings. This dust bag is preferably made of paper and includes a dirt storing portion 186a and a tubular inlet 186b adapted to be slipped over the end of tubular member 161, defining the exhaust of fan chamber 159. The garter spring 164 then clamps the tubular portion 186b of dust bag 186 in sealed relationship with tubular member 161. The disposable bag 186 is preferably pleated so that it can be folded into a very small unit for storage purposes. Moreover, it is made of a paper having the desired porosity to permit the desired air flow therethrough and, at the same time, retain therein the dust and dirt collected. The replacement of a filter bag is a very simple matter since all the housewife does is to remove the dust bag cover 41, affording ready access to the disposable bag 186. The dust bag clamping member or garter spring 164 is then removed, which permits ready removal of the filled dust bag and insertion of a new dust bag. A very large capacity bag can be employed in the space provided by dust bag chamber 43.

It will be appreciated that if for any reason the disposable dust bag 186 should be torn or otherwise empties its contents into the chamber 43, these contents of dirt and the like would fall into the motor chamber 44 and into the electric motor 178, which is very undesirable. To prevent this, there is provided a secondary filter 190 (FIGS. 2 and 4) preferably formed of a flocked wire cloth, which will prevent dust and dirt from passing therethrough, but which will permit the air produced by the fan 180 and discharged through the dust bag 186 to pass therethrough and out of the openings 57 defined in upper housing 24. So that there will be provided the desired

exhaust air passageway permitting this air to flow over motor 178 to cool the same, there are provided a pair of spacer members 192 (FIGS. 1 and 2) which may be glued or otherwise secured to what defines the bottom of container 40 thereby defining an air space between this bottom and the secondary filter 190. Furthermore, this space will also accommodate the power cord coming from handle portion 25 and connected to motor 178 and lamp 51.

10 In order to seal the secondary filter around the tubular exhaust member 161 of the motor and fan unit, the filter 190 is recessed or notched and a suitable gasket 193 (FIG. 4) provides the desired seal. Preferably, also cover member 42 is provided with a depending projection 42c which is shaped to conform to the other side of tubular exhaust passageway 161. It will be apparent that secondary filter 190 effectively divides the upper housing 24 into the dust bag chamber 43 and the fan and motor chamber 44.

20 In order that it may be possible to permit the fan to operate when attachments are to be applied to the vacuum cleaner 20 of the present invention without driving the rotatable brush and beater unit 84, the pulley 101 is connected to the motor shaft 179 through a clutch, generally designated as 194 (best shown in FIG. 11 of the drawings). As there illustrated, the motor shaft 179 projecting beyond the fan 180 and extending into the drive chamber 63 includes an axial recess 195 for receiving a clutch actuating push pin 196. The motor shaft 179 also includes an elongated slot 197 therethrough which intersects the recess 195. A pin 198 is disposed within the elongated transverse recess 197 and extends through an opening in push pin 196. A suitable compression spring 199 interposed between a washer 200 seated in a groove in shaft 179 and the pin 198 biases the clutch actuating push rod 196 to the position shown in FIG. 11 of the drawings. The pulley 101 includes a bearing 202 concentric with the pulley, which bearing and pulley are rotatably mounted on the end of motor shaft 179. The pulley 101 further includes slots 203 at the end thereof adjacent pin 198, into which the push rod pin 198 may move. When pin 198 is in slots 203, the pulley 101 is drivingly connected to the shaft 179. When the push rod 196 is depressed, so as to move push rod pin 198 out of the slots 203, the drive between the shaft 202 and pulley 101 is broken and shaft 179 is free to rotate in the bearing 202 in the pulley 101. A suitable protective sleeve 204 surrounds the portion of pulley 101 containing slots 203 and rotates therewith to protect the compression spring and the other parts housed therein. It will be apparent that depression of the push rod 196 will interrupt the drive between the pulley 101 and the motor shaft 179 and, hence, will interrupt the drive to the rotatable brush and beater arrangement 84.

55 As best illustrated in FIG. 13 of the drawings, when it is desired to apply an attachment to the vacuum cleaner 20 for cleaning upholstery and the like, the cover 65 is removed thereby exposing the end of push rod 196 through an opening 205 provided in cover 42, as clearly shown in FIG. 11 of the drawings. An attachment, generally designated as 206, is provided with a projection 206a, which, when the attachment is inserted into the crescent-shaped opening 64, engages the push rod 196 and disables the driving connection between the motor and fan unit 54 and the jack shaft 96. At the same time, the extension 206 includes a portion 206b which is inserted in the scroll-like suction passageway 62 and closes off this suction passageway to the primary suction nozzle 151 with the result that the mere insertion of the attachment 206 into the crescent-shaped opening 64 not only terminates the suction of the primary nozzle and causes all suction to be applied to the attachment 206, but at the same time disables the driving connection between the motor and the brush and beater arrangement 84. If

desired, a gasket 207 may be attached to the end of attachment 206.

In view of the detailed description included above, the operation of the suction cleaner 20 of the present invention will readily be understood. It will be appreciated that when the motor and fan unit 54 is energized and the cover 65 closes the crescent-shaped opening 64, air is drawn through the section nozzle 151 in the unit 21 and passes through the pores in the disposable bag 186, leaving dust and dirt particles inside the bag. The air then passes through the secondary filter 190 surrounding the motor unit, which filters out any remaining dust particles which would damage the motor. Air then passes over the motor and exhausts through the passageways 157, this air cooling the motor unit. By virtue of the counterbalancing arrangement described above, the person using the cleaner is not aware of the weight of the upper housing or the weight of the motor and fan unit contained therein. Since the upper housing is pivoted to the lower housing on the axis of the jack shaft 96, a driving connection between the brush and beater arrangement 34 and the motor unit 54 is accomplished which can be interrupted by actuating the clutch 194 described above.

While there has been shown and described a particular embodiment of the present invention, it will be apparent to those skilled in the art that various changes and modifications may be made without departing from the invention in its broader aspects, and it is, therefore, contemplated in the appended claims to cover all such changes and modifications that fall within the true spirit and scope of the invention.

What is claimed as new and desired to be secured by Letters Patent of the United States is:

1. A suction cleaner comprising, an upper housing, a handle member connected to said upper housing, a lower housing defining a section nozzle therein, pivot means pivotally relating said lower and upper housings at the portion of said upper housing remote from said handle member, suction producing means mounted in said upper housing, suction passageway means in said housings interconnecting said suction producing means and said suction nozzle, counterbalancing means including a torsion spring coiled about an axis displaced from the pivotal axis of said housings and having one end thereof fixed relative to one of said housings, and a ribbon spring effectively relating the other end of said torsion spring with the other of said housings to counterbalance the weight of the suction producing means in said upper housing.

2. A suction cleaner as set forth in claim 1 above wherein said suction producing means includes an electric motor, a rotatable brush mounted in said lower housing adjacent said suction nozzle, and drive means interconnecting said electric motor and said brush throughout the angular relationship of said pivotally related housings.

3. A suction cleaner as set forth in claim 2 wherein said pivot means includes a pair of spaced end bearings provided in said lower housing with coaxially aligned cylindrical bearing surfaces, and a cylindrical swivel portion formed in said upper housing pivotally supported from said cylindrical bearing surfaces, wherein said suction passageway means includes an opening provided in one of said end bearings, and wherein said drive means includes a jack shaft mounted in the other one of said end bearings on an axis coincident with the pivotal axis of said upper housing.

4. A vacuum cleaner comprising, a lower housing defining a suction nozzle therein, a pair of spaced end bearings provided with coaxially aligned cylindrical bearing surfaces, an upper housing provided with a cylindrical swivel portion pivotally supported from said cylindrical bearing surfaces, suction producing means including an electric motor mounted in said upper housing, suction passageway means in said housings interconnect-

ing said suction producing means and said nozzle, a rotatable brush mounted in said lower housing adjacent said suction nozzle, drive means interconnecting said electric motor and said brush throughout the angular relationship of said pivotally related housings, counterbalancing means including a counterbalancing drum journaled for rotation relative to said lower housing about an axis displaced from the pivotal axis of said pivotally related housings, a coiled torsion spring housed within said drum and having one end stationary relative to said lower housing and having its other end fixed relative to said drum so that rotation of said drum will torsionally stress the torsion spring, and a ribbon spring interrelating the counterbalancing means and the upper housing and having one end thereof connected to the exterior of said drum so as effectively to be capable of being wound on said drum with rotation thereof and passing over the cylindrical swivel portion of said upper housing.

5. A vacuum cleaner as set forth in claim 4 wherein the suction producing unit is mounted close to the pivotal axis of said housings.

6. In a vacuum cleaner of the type adapted to receive a vacuum attachment having a crescent-shaped suction passageway portion and a projection adjacent said portion, a housing defining a suction nozzle therein, suction-producing means carried by said housing and including a fan and an electric motor having a motor shaft, said fan being provided with a scroll-like fan suction inlet chamber having a crescent-shaped suction passageway, a rotatable brush mounted in said housing, a second suction passageway means interconnecting the first-mentioned suction passageway and said suction nozzle, said second suction passageway being provided with a crescent-shaped opening aligned with said crescent-shaped suction passageway, means drivingly interrelating said motor and said rotatable brush and including a normally engaged clutch, said crescent-shaped suction passageway surrounding said clutch, said clutch including a drive pulley concentrically positioned on said motor shaft rotatably mounted thereon and including slots in one hub thereof, said motor shaft being provided with an axial recess, a clutch actuating push pin positioned in said axial recess, a drive pin disposed in an elongated transverse slot in said motor shaft and extending through an opening in said push pin, a compression spring biasing said drive pin into driving engagement with said slots in said hub of said pulley whereby depression of said push pin is effective to disable said clutch, said housing being provided with an opening aligned with said push pin, and a removable cover normally closing said crescent-shaped opening and the last-mentioned opening.

7. In combination, the vacuum cleaner as set forth in claim 6 and an attachment of the type having a crescent-shaped passageway portion extending through said crescent-shaped opening and provided with a projection extending through the last-mentioned opening wherein the removal of said cover and mere insertion of the attachment into the crescent-shaped opening terminates the suction to the suction nozzle and connects the suction from the suction-producing means to the attachment, and at the same time the projection on the attachment extends through the last-mentioned opening to engage the push pin and disable the driving connection between the motor and the brush means.

8. In a vacuum cleaner of the type adapted to receive an attachment having a suction passageway portion and a projection adjacent said portion, a housing defining a suction nozzle therein, suction-producing means carried by said housing and including a fan and an electric motor having a motor shaft, a rotatable brush mounted in said housing, suction passageway means interconnecting said suction-producing means and said suction nozzle and provided with an attachment opening, means drivingly interrelating said motor and said rotatable brush and including a normally engaged clutch disposed at one

end of said motor shaft, said clutch including a drive pulley concentrically positioned on said motor shaft rotatably mounted thereon and including slots in the hub thereof, said motor shaft being provided with an axial recess at said one end, a clutch actuating push pin positioned in said axial recess, said housing being provided with an opening aligned with said push pin, said last-mentioned opening being adjacent said one end of said motor shaft, a drive pin disposed in an elongated transverse slot in said motor shaft and extending through an opening in said push pin, a compression spring biasing said drive pin into driving engagement with said slots in said pulley whereby depression of said push pin is effective to disable said clutch, and a removable covering normally closing said attachment opening and the housing opening wherein the removal of said cover and mere insertion of the attachment into the vacuum opening is effective at the same time to engage the push pin with the projection of the attachment thereby to disable the driving connection between the motor and the brush means.

9. The vacuum cleaner of claim 8 wherein said attachment opening is crescent shaped.

10. In a vacuum cleaner of the type adapted to receive an attachment having a crescent-shaped suction passageway portion and a projection adjacent said portion, an upper housing, a handle member connected to said upper housing, a lower housing defining a suction nozzle therein, suction producing means carried by said upper housing and including a fan and an electric motor having a motor shaft, pivot means pivotally relating said upper and lower housings at the portion of said upper housing remote from said handle member, said fan being provided with a scroll-like suction inlet chamber in said upper housing having a crescent-shaped passageway, a rotatable brush mounted in said lower housing, suction passageway means interconnecting said passageway and said

5
